(57) **CLAIM**

The ornamental design for a thrombectomy handle assembly, as shown and described.

DESCRIPTION

FIG. 1 is a perspective view of a thrombectomy handle assembly, showing our new design.

FIG. 2 is a front view of the thrombectomy handle assembly, showing our new design.

FIG. 3 is a rear view of the thrombectomy handle assembly, showing our new design.

FIG. 4 is a top plan view of the thrombectomy handle assembly, showing our new design.

FIG. 5 is a bottom plan view of the thrombectomy handle assembly, showing our new design.

FIG. 6 is a right side view of the thrombectomy handle assembly, showing our new design.

FIG. 7 is a left side view of the thrombectomy handle assembly, showing our new design; and,

FIG. 8 is a left side view of a thrombectomy handle assembly, with a slider of the thrombectomy handle assembly shown pulled back and a basket assembly of the thrombectomy device shown in an expanded state. The basket assembly and connecting shaft of the thrombectomy device are shown in broken lines for illustrating environmental structure only and form no part of the claimed design.

The broken lines showing in the drawings are included for the purpose of illustrating environmental structure of the thrombectomy handle assembly and form no part of the claimed design.
